(57) **CLAIM**

The ornamental design for a forearm trainer, as shown and described.

DESCRIPTION

FIG. 1 is a front perspective view of a forearm trainer, showing my design.

FIG. 2 is a front elevation view of the forearm trainer of FIG. 1.

FIG. 3 is a left side elevation view of the forearm trainer of FIG. 1.

FIG. 4 is a right side elevation view of the forearm trainer of FIG. 1.

FIG. 5 is a top plan view of the forearm trainer of FIG. 1.

FIG. 6 is a bottom plan view of the forearm trainer of FIG. 1.

FIG. 7 is a perspective view of the forearm trainer of FIG. 1 wherein a hook of the forearm trainer is loaded with weight pieces.

FIG. 8 is another perspective view of the forearm trainer of FIG. 1 wherein the hook of the forearm trainer is loaded with weight pieces and a rod of the forearm trainer being pulled by a person.

FIG. 9 is an enlarged view of an area labeled 9 in FIG. 1.

FIG. 10 is an enlarged view of an area labeled 10 in FIG. 1.

FIG. 11 is a front perspective view of another embodiment of a forearm trainer.

FIG. 12 is a front elevation view of the forearm trainer of FIG. 11.

FIG. 13 is a left side elevation view of the forearm trainer of FIG. 11.

FIG. 14 is a right side elevation view of the forearm trainer of FIG. 11.

FIG. 15 is a top plan view of the forearm trainer of FIG. 11; and,

FIG. 16 is a bottom plan view of the forearm trainer of FIG. 11.

The broken lines in the drawings depict environmental structure and form no part of the claimed design.
